SIMEON B. KIRTLEY, OF COLUMBIA, MISSOURI.

ACCOUNT-LEDGER.

1,399,776.

Specification of Letters Patent. Patented Dec. 13, 1921.

Application filed March 1, 1920. Serial No. 362,277.

To all whom it may concern:

Be it known that I, SIMEON B. KIRTLEY, a citizen of the United States, residing at Columbia, Boone county, Missouri, have invented a new and useful Improvement in Account-Ledgers, of which the following is a specification.

This invention relates to account ledgers.

An object of the invention is to provide an account ledger containing series of master index sheets each adapted to contain the record of an account or accounts and provided with visible indexes on the sheets respectively, all arranged so that when the ledger is opened the master indexes are visible; the ledger also being provided with one or more division sheets containing series of indexes corresponding to and in alinement with the indexes on the master index sheets, and with identifying characters corresponding to cut away portions of the master index sheets.

Another object of the invention is to provide an account ledger containing series of master index sheets each adapted to contain the record of an account or accounts and provided with visible indexes on the sheets respectively, all arranged so that when the ledger is opened the master indexes are visible; the ledger also being provided with one or more division sheets containing series of indexes corresponding to and in alinement with the indexes on the master index sheets, and with identifying characters corresponding to cut away portions of the master index sheets, in combination with one or more transfer indexes for indexing the names of accounts transferred.

A further object of the invention is to provide an improved system of transferring accounts so that by simply referring to the transfer index any account which has been transferred may be quickly identified and located without reference to the transfer ledger.

Other objects of the invention will appear from the following description, reference being made to the drawing, in which—

Figure 1 is a view showing one form of master indexes on the cut away portions of master index sheets and also showing the division sheet and the indexes thereon in alinement with and identifying the indexes on the master index sheets.

Fig. 2 is a similar view showing another form of master indexes on the cut away portions of the master index sheets.

Fig. 3 is a view showing a portion of the open ledger to illustrate the index of transferred accounts, and the manner in which the transferred accounts are indexed for easy reference and location.

The sheets in each book or ledger are divided into any desired number of series and a selected number of sheets may be assigned to each individual master index. The number of sheets which should be assigned to each index, of course, varies in proportion to the frequency of the need for use of the respective master indexes as determined or ascertained by experience and observation, or by individual requirements in different instances. Also, in case in which any index is used so frequently that it is rendered impracticable to place in one series all of the master indexes in visible relation on the cut away portions at the top of the sheets, as hereinafter explained, such index may be provided with any number of series of master index sheets.

Referring now to the particular construction and arrangement shown in Fig. 1 of the drawing, the ledger is open before one of the division sheets. The division sheet 25 is formed with a cut away portion extending transversely at its upper edge so as to disclose all of the master indexes on a series of master index sheets which are cut away in stepped relation to provide exposed portions on which the master indexes are placed.

As shown in Fig. 1 there is a series of master index sheets 26. The master index sheets are cut away in stepped relation so that when the book is open all of the master indexes of the exposed series are visible. A preferred system of master indexing is shown in Fig. 1, in which the last master index sheet of the series is not cut away but is of full size, and I prefer to index that particular sheet with a distinguishing master index character 26^a so as to designate that it is the last sheet of the series and is not cut away. As shown in Fig. 1, the master indexing character 26^a on the last sheet of the series comprises the letter "A." The last cut away master index sheet is indexed on the exposed portion thereof with a master index 26^b comprising the numeral "1" and the exposed portions of the remaining index sheets are indexed consecutively with master index 26^c comprising the numerals "2," "3," "4," etc. These indexes may be placed on the exposed indexing portions of the sheets

at any time and as the indexes are of a very short and simple character they may be placed on the sheets quickly. Moreover, the indexes are readily distinguishable from each other.

Before any selected ones of the master index sheets, as well as before each series of master index sheets may be any desired number of insert sheets 27 that are governed by the different master indexes. The insert sheets are also cut away in stepped relation to provide exposed portions on which the name of the person or concern having an account or accounts entered on the respective sheets may be written. This is apparent by reference to Fig. 1, in which names appear on certain of the insert sheets that are indexed under and governed by the master indexes of the series to which the insert sheets belong, and the division sheet belonging to that series of master index sheets.

Each master index sheet, as well as each insert sheet, is provided with a series of designating characters 28 corresponding to and in alinement with the cut away portions of all of the sheets so that said designating characters 28 indicate the positions of all of the master indexes as well as the cut away portions of the insert sheets. The designating characters 28 are arranged transversely on each master index sheet and on each insert sheet immediately below the cut away portion of such sheet, and immediately above the marginal edge of the cut away portion of the division sheet 25, so that said characters 28 are visible while the division sheet rests on the insert and master index sheets as shown in Figs. 1 and 2.

The division sheet 25 is provided with a similar series of identifying characters 29 to identify the master indexes contained on the division sheet and by corresponding with the designating characters 28 to indicate to which of the master index sheets the various sub-indexes belong.

The division sheet 25, adjacent to its upper marginal cut away edge, is provided with a series of master indexes 30 corresponding to and in alinement with all of the master indexes on the exposed cut away portions of the master index sheets. For certain of the master indexes 30 contained upon the division sheet there are provided in alinement therewith as many sub-indexes 31 as there are sub-indexes in the series of sheets belonging to each master index sheet. Thus names beginning with "Aa" and with "Ab" are indexed in alinement with the master index "Ac," and the master index "Ac" on the division sheet is in alinement with and is governed by a single one of the master indexes on the exposed portion of one of the master index sheets.

As the letter "C" immediately precedes the letter "D" in the alphabet no sub-indexes for

the master index "Ad" on the division sheet 25 are required; but there are a number of sub-indexes between the master index "Ad" and the master index "Al". These sub-indexes as shown comprise several of the first letters of sur-names beginning with "Ac," "Af," "Ag," "Al," "Ai," "Aj" and "Ak," and other letters in addition to the first two letters may be added to distinguish different names from each other, as desired.

The construction and arrangement shown in Fig. 2 differs only from the construction and arrangement shown in Fig. 1 in the matter of the master indexes on the exposed portions of the master index sheets. In Fig. 2 the master indexes on the master index sheets, which master indexes are designated by 26^a are somewhat more elaborate than the master index character 26^a and the master indexes 26^b and 26^c shown on the master index sheets in Fig. 1. For instance, in Fig. 2, the master indexes 26^d on the exposed portions of the master index sheets comprise in each instance a number of the first letters included in sur-names. These letters may be applied in any desired manner, as by writing the indexes on the exposed portions of the sheets, or by pasting stickers containing the indexes upon the exposed portion of the sheets. Since the same elements are shown in Fig. 2 that are shown in Fig. 1, the same reference numerals are applied to the elements of Fig. 2 that are applied to corresponding elements in Fig. 1.

The list and index of transferred accounts, included as a part of my invention, are shown in Fig. 3. As shown in Fig. 3 the index for the transferred accounts is arranged on the inner or reverse side of the division sheet. As shown the division sheet is divided into a number of vertical columns 32, and the vertical columns are divided into horizontal spaces adapted to receive the names of accounts transferred. A master index 33 is arranged vertically at one or both vertical edges of the division sheet and, if desired, a similar master index may be arranged elsewhere upon the division sheet so that the accounts transferred may be readily identified in connection with the master index under which the accounts were entered. For each name column 32 there is provided a column 34 containing spaces to receive a character corresponding to one of the characters 28 which identifies the position to which the sheet containing the transferred account was cut. For instance, the transferred account of "C. W. Acton" is indexed under the master index "6" (Fig. 1) of the master index sheets and under the index "Ac" in the index 30 on the division sheet. Thus, when the account of C. W. Acton is transferred, his name is written in the proper column in association with the index character "6" in the master index 33; and the

index character "8" is written in alinement with the name C. W. Acton in the column 34, thus clearly indexing the transferred account of C. W. Acton as having been transferred from a master index sheet whose cut away portion was designated by "8" to an insert sheet in front of the master index "6," which insert sheet has a cut away portion in alinement with "8" of the designating 10 characters 28 and the identifying characters 29. This enables the user to ascertain quickly and conveniently that the space belonging to this transferred account must or should be reserved for future use of the account in 15 case the account again becomes an active account. Other accounts governed by the same master index will be entered upon sheets cut away beyond the sheet containing the Acton account; as, for instance, the account of 20 "Acme" is shown as being entered upon a sheet cut away beyond the sheet containing the Acton account.

What I claim and desire to secure by Letters Patent, is:—

25 1. An account ledger, having series of master index sheets cut away in stepped relation to form a visible space upon each sheet of the series for the reception of a master index; a master index on the visible space of 30 each of said sheets; a series of insert sheets before the series of master index sheets cut away in stepped relation to expose all of the master indexes of the series to which the insert sheets belong and to provide visible 35 spaces adapted to have entered therein identifications of the accounts contained on said insert sheets respectively; and a division sheet, before the series of master index sheets and insert sheets, having designating 40 characters thereon indicating respectively the positions of all of the master indexes and also the positions of the cut away portions of the visible index sheets.

2. An account ledger, having series of 45 master index sheets cut away in stepped relation to form a visible space upon each sheet of the series for the reception of a master index; a master index on the visible space of each of said sheets; a series of insert 50 sheets before the series of master index sheets cut away in stepped relation to expose all of the master indexes of the series to which the insert sheets belong and to provide visible spaces adapted to have entered therein 55 indications of the accounts contained on said insert sheets respectively; and a division sheet, before the series of master index sheets and insert sheets, having designating characters thereon indicating the positions 60 of the cut away portions of the index sheets.

3. An account ledger, having series of master index sheets cut away in stepped relation to form a visible space upon each sheet 65 of the series for the reception of a master

index; a master index on the visible space of each of said sheets; a series of insert sheets before the series of master index sheets cut away in stepped relation to expose all of the master indexes of the series to which the 70 insert sheets belong and to provide visible spaces adapted to have entered therein identifications of the accounts contained on said insert sheets respectively; a division sheet, before the series of master index sheets and 75 insert sheets, having designating characters thereon indicating the positions of all of the master indexes and also the positions of the cut away portions of the visible index sheets; and master indexes on the division sheet in 80 alinement with the master indexes on the master index sheets, and with the designating characters which designate the positions of said indexes.

4. An account ledger, having series of 85 master index sheets cut away in stepped relation to form a visible space upon each sheet of the series for the reception of a master index; a master index on the visible space of each of said sheets; a series of insert sheets 90 before the series of master index sheets cut away in stepped relation to expose all of the master indexes of the series to which the insert sheets belong and to provide visible spaces adapted to have entered therein identifications of the accounts contained on said insert sheets respectively; a division sheet, before the series of master index sheets and insert sheets, having designating characters thereon indicating the positions of the cut 95 away portions of the insert sheets; and master indexes on the division sheet in alinement with the master indexes on the master index sheets.

5. An account ledger, having series of 105 master index sheets cut away in stepped relation to form a visible space upon each sheet of the series for the reception of a master index; a master index on the visible space of each of said sheets; a series of insert sheets 110 before the series of master index sheets cut away in stepped relation to expose all of the master indexes of the series to which the insert sheets belong and to provide visible spaces adapted to have entered therein identifications of the accounts contained on said insert sheets respectively; a division sheet, before the series of master index sheets and insert sheets, having designating characters 115 thereon indicating the positions of all of the master indexes and also the positions of the cut away portions of the visible index sheets; master indexes on the division sheet in alinement with the master indexes on the master index sheets; and a series of sub-indexes on 120 the division sheet belonging to the master index sheets.

6. An account ledger, having series of master index sheets cut away in stepped relation to form a visible space upon each sheet 130

- of the series for the reception of a master index; a master index on the visible space of each of said sheets; a series of insert sheets before the series of master index sheets cut away in stepped relation to expose all of the master indexes of the series to which the insert sheets belong and to provide visible spaces adapted to have entered therein identifications of the accounts contained on said insert sheets respectively; a division sheet, before the series of master index sheets and insert sheets having designating characters thereon indicating the positions of all of the master indexes and also the positions of the cut away portions of the visible index sheets; and a master index on the division sheet corresponding to the master indexes on the master index sheets for indicating transferred accounts. 5
10. An account ledger, having series of master index sheets cut away in stepped relation to form a visible space upon each sheet of the series for the reception of a master index; a master index on the visible space of each of said sheets; a series of insert sheets before the series of master index sheets cut away in stepped relation to expose all of the master indexes of the series to which the insert sheets belong and to provide visible spaces adapted to have entered therein identifications of the accounts contained on said insert sheets respectively; a division sheet, before the series of master index sheets and insert sheets, having designating characters thereon indicating the positions of the cut away portions of the index sheets; master indexes on the division sheet in alinement with the designating characters thereon and with the master indexes on the master index sheets; and a master index on the division sheet corresponding to the master indexes on the master index sheets for indicating transferred accounts. 15
20. 7. An account ledger, having series of master index sheets cut away in stepped relation to form a visible space upon each sheet of the series for the reception of a master index; a master index on the visible space of each of said sheets; a series of insert sheets before the series of master index sheets cut away in stepped relation to expose all of the master indexes of the series to which the insert sheets belong and to provide visible spaces adapted to have entered therein identifications of the accounts contained on said insert sheets respectively; a division sheet, before the series of master index sheets and insert sheets, having designating characters thereon indicating the positions of the cut away portions of the index sheets; and a master index on the division sheet corresponding to the master indexes on the master index sheets for indicating transferred accounts. 25
30. 8. An account ledger, having series of master index sheets cut away in stepped relation to form a visible space upon each sheet of the series for the reception of a master index; a series of insert sheets before the master index sheets cut away in stepped relation to provide visible spaces adapted to have entered therein identifications of the accounts contained on said insert sheets respectively; a division sheet, before the series of master index sheets and insert sheets, having designating characters thereon indicating the positions of all of the master indexes and also the positions of the cut away portions of the visible index sheets; master indexes on the division sheet in alinement with the designating characters thereon and with the master indexes on the master index sheets; a series of sub-indexes on the division sheet belonging to the master indexes on the division sheet; and a master index on the division sheet corresponding to the master indexes on the master index sheets for indicating transferred accounts. 35
40. 9. An account ledger, having series of master index sheets cut away in stepped relation to form a visible space upon each sheet of the series for the reception of a master index; a series of insert sheets before the master index sheets cut away in stepped relation to provide visible spaces adapted to have entered therein identifications of the accounts contained on said insert sheets respectively; a division sheet, before the series of master index sheets and insert sheets, having designating characters thereon indicating the positions of all of the master indexes and also the positions of the cut away portions of the visible index sheets; master indexes on the division sheet in alinement with the designating characters thereon and with the master indexes on the master index sheets; and a master index on the division sheet corresponding to the master indexes on the master index sheets for indicating transferred accounts. 45
50. 10. An account ledger, having series of master index sheets cut away in stepped relation to form a visible space upon each sheet of the series for the reception of a master index; a series of insert sheets before the master index sheets cut away in stepped relation to provide visible spaces adapted to have entered therein identifications of the accounts contained on said insert sheets respectively; a division sheet, before the series of master index sheets and insert sheets, having designating characters thereon indicating the positions of all of the master indexes and also the positions of the cut away portions of the visible index sheets; master indexes on the division sheet in alinement with the designating characters thereon and with the master indexes on the master index sheets; and a master index on the division sheet corresponding to the master indexes on the master index sheets for indicating transferred accounts. 55

SIMEON B. KIRTLEY.
